P. E. YEAGER,
 MODIFYING ATTACHMENT FOR SOUND REPRODUCING MACHINES,
 APPLICATION FILED APR. 2, 1920.
1,377,652. Patented May 10, 1921.

UNITED STATES PATENT OFFICE.

PETER E. YEAGER, OF READING, PENNSYLVANIA.

MODIFYING ATTACHMENT FOR SOUND-REPRODUCING MACHINES.

1,377,652.

Specification of Letters Patent.

Patented May 10, 1921.

Application filed April 2, 1920. Serial No. 370,788.

To all whom it may concern:

Be it known that I, PETER E. YEAGER, a citizen of the United States, residing at Reading, in the county of Berks and State 5 of Pennsylvania, have invented certain new and useful Improvements in Modifying Attachments for Sound-Reproducing Machines, of which the following is a specification, reference being had to the accompanying drawings.

This invention relates to certain improvements in modifying attachments for sound reproducing machines, and it is an object of the invention to provide a novel and 15 improved device of this general character especially designed and adapted for use in connection with the stylus arm or lever of a sound box whereby the sounds reproduced by the machine are substantially free of 20 scratching or other foreign noises which are often present in the sounds produced by the machines now generally in use.

Another object of the invention is to provide a novel and improved attachment of 25 this general character which operates to materially increase the quality and tone of the sounds reproduced, and which also operates to lower the pitch or tone of such sounds so that the tone is full, resonant and 30 natural, and whereby the tones or sounds are reproduced with fidelity.

It is also an object of the invention to provide a novel and improved attachment of this general character comprising a chamber 35 provided with means therein operating to substantially eliminate foreign vibrations such as scratching or the like so that the tones produced within the sound box are substantially an exact reproduction of the 40 original.

The invention consists in the details of construction and in the combination and arrangement of the several parts of my improved attachment whereby certain important advantages are attained and the device rendered simpler, less expensive and otherwise more convenient and advantageous for use, as will be hereinafter more fully set forth.

50 The novel features of my invention will hereinafter be definitely claimed.

In order that my invention may be the better understood, I will now proceed to de-

scribe the same with reference to the accompanying drawings, wherein:

55 Figure 1 is a fragmentary view in front elevation illustrating a sound box having coacting therewith attachments constructed and applied in accordance with an embodiment of my invention;

60 Fig. 2 is a view in side elevation of the structure as illustrated in Fig. 1;

65 Fig. 3 is an enlarged fragmentary view partly in section and partly in elevation illustrating certain details of construction of one of my improved attachments; and

70 Fig. 4 is a view in bottom plan of the structure illustrated in Fig. 3 with the stylus or pin removed.

75 As disclosed in the accompanying drawings, S denotes a sound box of any ordinary or preferred type and which has operatively engaged with the diaphragm 1 a stylus arm or lever A. As herein embodied, the stylus arm A comprises two sections 2 and 3 having 80 interposed therebetween an attachment B constructed in accordance with an embodiment of my invention, and which attachment also connects the adjacent end portions of the sections 2 and 3. The lower or outer 85 end portion of the section 3 of the stylus arm or lever A is provided with a socket 4 which ordinarily receives a conventional type of stylus or pin, but, which, in the present embodiment of my invention, is adapted 90 to afford means whereby a second attachment B', constructed in accordance with an embodiment of my invention, may be operatively connected with the stylus arm or lever A.

95 As herein disclosed, the attachments B and B' are of similar construction, and each of said attachments comprises a shell 5 having a central portion provided with a substantially spherical chamber 6 of desired radius and with its opposite end portions provided with the longitudinally aligned openings 7 in communication with the chamber 6. The shell 5 is preferably made of wood and snugly engaged within each of the openings 7 is a sleeve or bushing 8 of hard wood.

100 Initially, the shell 5 is divided longitudinally into two duplicate sections, and when said sections are assembled, the opposed edges or walls are adapted to be adhesively connected.

- Each of the sections of the shell is provided at one end portion at opposite sides of the opening 7 with the grooves 9 arranged in parallelism and in which are seated the opposite end portions of a cluster of elongated wire strands 10 of soft metal. The strands 10 are extremely fine and the end portions 10^a thereof seating within the grooves 9 are preferably twisted or wrapped together, and said portions 10^a are preferably held against displacement within the grooves 9 by glue or other suitable adhesive. The portions of the strands 10 intermediate the wrapped or twisted portions 10^a are disconnected or free one from the remainder, and after the portions 10^a have been properly engaged within the grooves 9, said free intermediate portions of the strands are spread or separated within the section of the chamber 6 and substantially in close contact with the wall of said chamber. After the strands 10 have been properly arranged within each section of the shell 5, said sections are then assembled.
- It is also preferred in practice that initially the opposite ends of the sections of the shell 5 be solid, and after the sections have been assembled the openings 7 are bored therethrough by a suitable tool.
- After the openings 7 have been formed, it is preferred that a solid plug or filler of hard wood be snugly engaged therein, and then bored out to provide the sleeve or bushing 8. It is also preferred that each of the bushings or sleeves 8 be positively retained within an opening 7 by a suitable adhesive, as by this means the maintenance of the sections of the shell 5 assembled is materially facilitated.
- The upper opening 7 of the attachment B is adapted to have snugly engaged therein the outer end portion of the section 2 of the stylus arm or lever A, while the opposite or lower opening 7 is adapted to have snugly engaged therein the adjacent end portion of the section 3 of said stylus arm or lever A. To further facilitate the positive connection between the section 3 and the attachment B, the lower part of the attachment B has disposed therearound a ferrule or band 11 preferably of soft metal and threaded through said band 11 and the adjacent wall of the shell 5 is a binding screw 12 which is adapted to have requisite gripping contact with the section 3.
- The lower or outer end portion of the attachment B' is also surrounded by a band or ferrule 11 preferably of soft metal, through which is disposed the binding screw 14 which also extends through the adjacent wall of the shell 5 and is adapted to have binding action on the end portion of the needle or stylus 15 inserted within the lower portion 7. The upper or inner opening 7 of the attachment B' is adapted to have

snugly engaged therein an end portion of a coupling rod 16 of soft metal, and the opposite end portion of said rod 16 is adapted to extend within the socket 4 of the section 3 and held therein by the binding screw 17 threaded through a wall of the section 3 and having binding action on the pin 16.

It is also preferred that the section 3 of the arm or lever 9 have the requisite pivotal connection, as at 18, with the sound box S, as is clearly illustrated in Figs. 1 and 2 of the accompanying drawings.

While I disclose in the accompanying drawings the use of two attachments B and B', it is to be understood that either one of said attachments can be omitted, and in the event the attachment B is not used, the stylus arm or lever will be of any one of the types now in use or which may be employed. It has been established in practice that the use of one attachment is of decided advantage, and when only a single attachment is preferred, it is desired that the same be positioned and arranged as illustrated in the accompanying drawings with respect to the attachment B'.

With the use of my improved attachment or attachments in connection with the stylus arm or lever of a sound box, it has been fully established in actual practice that the sounds are reproduced with fidelity in the sound box and the tones emitted therefrom full, resonant and natural, with foreign noises, such as scratching, substantially eliminated entirely. It has also been established in practice that the tones reproduced with the use of my improved attachment or attachments is lower whereby the quality of such tones is materially increased.

It has also been fully established in practice that the foregoing advantageous results are accomplished and facilitated by the strands 10 as the clarifying of the tones is effected by the supplemental vibrations of such strands.

From the foregoing description it is thought to be obvious that an attachment constructed in accordance with my invention is particularly well adapted for use by reason of the convenience and facility with which it may be assembled and operated, and it will also be obvious that my invention is susceptible of some change and modification without departing from the principles and spirit thereof, and for this reason I do not wish to be understood as limiting myself to the precise arrangement and formation of the several parts herein shown in carrying out my invention in practice except as hereinafter claimed.

I claim:

- As a new article of manufacture, a sound modifying attachment for use in connection with the stylus arm of a sound reproducing machine comprising a shell hav-

ing a chamber intermediate its ends, openings in its opposite ends, and a vibratory medium arranged within the chamber and substantially in contact with the wall of the chamber.

2. As a new article of manufacture, a sound modifying attachment for use in connection with the stylus arm of a sound reproducing machine comprising a shell having a chamber intermediate its ends, and openings in its opposite ends, and a vibratory medium arranged within the chamber, said vibratory medium comprising a plurality of metallic strands extending within the chamber, the portions of the strands within the chamber being separated, the opposite end portions of the strands being anchored to the shell to an end portion thereof.

10

15

3. As a new article of manufacture, a sound modifying attachment for use in connection with the stylus arm of a sound reproducing machine comprising a shell having a chamber intermediate its ends, openings in its opposite ends, and a vibratory medium arranged within the chamber, said vibratory medium comprising a plurality of metallic strands extending within the chamber, the portions of the strands within the chamber being separated, the opposite end portions of the strands being anchored to the shell to an end portion thereof.

In testimony whereof I hereunto affix my signature.

PETER E. YEAGER.
